COMBINED BUTTER DISH AND COVER

Simon H. Slobodkin, New York, N. Y., assignor to Canonsburg Pottery Company, Canonsburg,
Pa., a corporation of Pennsylvania

Application October 11, 1950, Serial No. 12,529

Term of patent 7 years

(Cl. D44—5)

To all whom it may concern:

Be it known that I, Simon H. Slobodkin, a citizen of the United States of America and a resident of New York, in the county and State of New York, have invented a new, original, and ornamental Design for a Combined Butter Dish and Cover, of which the following is a specification, reference being had to the accompanying drawing, forming a part thereof, in which:

Fig. 1 is a perspective exploded view of a combined butter dish and cover, showing my new design;

Fig. 2 is a top plan view showing the dish and cover in assembled condition;

Fig. 3 is a front elevational view thereof with the dish and cover in assembled condition; and

Fig. 4 is a longitudinal cross sectional view of the cover taken in the plane of the line 4—4 of Fig. 2.

I claim:

The ornamental design for a combined butter dish and cover, as shown.

SIMON H. SLOBODKIN.
